WILLIAM HAILES, OF ALBANY, NEW YORK.

Design No. 4,434, dated October 25, 1870.

DESIGN FOR A PARLOR-STOVE.

The Schedule referred to in these Letters Patent and making part of the same.

To all whom it may concern:

Be it known that I, WILLIAM HAILES, of the city and county of Albany and State of New York, have invented and produced a new and original Design for a Heating-Stove, named the Swiss Cottage, of which the following is a specification.

The nature of my design is fully represented in the accompanying photographic illustrations, to which reference is made; and I declare the annexed view exhibiting in perspective the stove, to be a full and accurate delineation of its plates with their ornaments,

parts of the stove not shown being symmetrically similar to the parts shown.

What I claim, and desire to secure by Letters Patent, is—

The design for a heating-stove, as herein shown and described.

WILLIAM HAILES.
